US00D699959S

(12) **United States Design Patent**
Smith et al.

(10) **Patent No.:** **US D699,959 S**
(45) **Date of Patent:** **** Feb. 25, 2014**

(54) **CHAIR**(71) Applicant: **Steelcase Inc.**, Grand Rapids, MI (US)(72) Inventors: **Bruce M. Smith**, East Grand Rapids, MI (US); **Glen Oliver Low**, Hamburg (DE); **James N. Ludwig**, East Grand Rapids, MI (US); **Robert J. Battey**, Middleville, MI (US); **Gordon Jay Peterson**, Rockford, MI (US)(73) Assignee: **Steelcase Inc.**, Grand Rapids, MI (US)(**) Term: **14 Years**(21) Appl. No.: **29/432,781**(22) Filed: **Sep. 20, 2012**(51) LOC (10) Cl. **06-01**

(52) U.S. Cl.

USPC ..... **D6/366**(58) **Field of Classification Search**

USPC D6/334-336, 364, 365, 366, 367, 374, D6/376, 379, 380, 716, 716.1, 716.2, D6/716.3, 716.4; 297/284.4, 298, 394, 297/396, 404, 411.27, 452.21, 452.29, 297/452.3, 452.32, 452.34, 452.48

See application file for complete search history.

(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.
